ATTORNEY:

UNITED STATES PATENT OFFICE.

JOHN R. McLAUGHLIN, OF HOLBROOK, MASSACHUSETTS.

LAST.

1,310,762.

Specification of Letters Patent. Patented July 22, 1919.

Application filed November 22, 1917. Serial No. 203,376.

To all whom it may concern:

Be it known that I, JOHN R. McLAUGHLIN, a citizen of the United States, residing at Holbrook, in the county of Norfolk and State of Massachusetts, have invented certain Improvements in Lasts, of which the following description, in connection with the accompanying drawings, is a specification, like reference characters on the drawings indicating like parts in the several figures.

It is the universal practice to use a sewing machine of the curved needle type to perform the outsole stitching operation on welt and stitch down shoes since practically all styles of shoes are so deeply cut in at the shank that a straight needle machine cannot operate satisfactorily along this portion of the shoe. At the same time the advantages of a straight needle sewing machine as compared with a curved needle machine, such for instance, as the reduced expense of straight needles and the lessened liability of their springing while in use, are well understood by those skilled in this art. It is considered essential to good shoe making to perform the outsole stitching operation while the last is in the shoe, and the present invention aims to devise a last suitable for use in the manufacture of welt and stitch down shoes which will permit the use of a straight needle sewing machine in securing the outsole to the shoe. The invention also aims to accomplish this result without sacrificing the style and attractive appearance of the shoe which the lasts now commonly used give to it.

The manner in which it is proposed to accomplish these objects and the various features of the invention will be readily understood from the following description, reference being made to the accompanying drawings, in which,

Figure 1 is a side elevation of a last embodying this invention;

Fig. 2 is a side elevation of a removable portion of the last shown in Fig. 1;

Fig. 3 is a side elevation of the last shown in Fig. 1 as it appears when the part shown in Fig. 2 is removed therefrom; and

Fig. 4 is a vertical, transverse, cross sectional view on the line 4—4, Fig. 1.

The last shown in Fig. 1 comprises a fore-part or toe portion A, an intermediate portion B and a heel portion C. The toe and heel portions A and C, respectively, are connected together by a metal plate which

preferably consists of two sections, a and b, hinged together at d. The intermediate portion B normally fits between the parts A and C to complete the last but is arranged to be removed therefrom while the last is in the shoe. For the purpose of holding the intermediate part B in its coöperative relationship to the parts A and C, the section a of the plate is provided with a post p, designed to enter a slot p', Fig. 3, in the forward part of the section B, and another post h secured in the upper part of the heel part C is designed to enter a hole h', Fig. 3, in the part B and coöperate with the post p to maintain the intermediate section B in its normal position. A recess g cut in the bottom of the intermediate section B receives the hinge d when the section B is in its normal position.

This last is designed to be used in the ordinary manner in manufacturing a shoe up to the time that the shoe is ready for the outsole stitching operation. At this time the intermediate section B is removed leaving the parts A and C in their normal positions in the shoe, in which positions they are held by the plate that connects them. It will be seen from an inspection of Fig. 1 that a space D is provided between the rear surface e of the section B and the forward surface f of the heel part C, so that no interference occurs between these two sections during the operation of withdrawing the intermediate section from the shoe. It will also be seen that the intermediate section B contains the upper supporting surfaces which overhang the tread face of the last and which would interfere with the use of a straight needle sewing machine. In other words, the removal of this section removes all lateral support for the upper of the shoe in the region of the shank. In fact, except for the strip opposite the plate sections a and b and which is so narrow as to be negligible, the upper has no lateral support from a point in the heel portion of the shoe to a point in front of the shank of the shoe. Consequently, the operator, in presenting the shoe to the outsole stitcher, can press these parts of the upper inwardly far enough to move them entirely out of the positions in which they would interfere with the operation of the sewing instrumentalities of a straight needle machine. The lateral surfaces of the parts A and C adjacent to the tread face of the last and the edge faces of the plate sections a and b lie sub-

stantially at right angles to the tread face of the last so that they not only do not interfere with the outsole stitching operation but facilitate this operation since these surfaces 5 adjacent to the tread face of the last may be utilized to guide the sewing instrumentalities during the outsole stitching operation. Since the part A, supporting the toe and instep surfaces of the upper, and the 10 part C at the heel, are held rigidly in properly spaced relationship by the metal plate sections *a* and *b*, and since these sections form a rigid support for the bottom of the shoe, the last gives the shoe all the support 15 that it requires during this operation. The hinging of the two sections of the plate together between the toe and heel parts of the last facilities the insertion of the last in a shoe and its removal therefrom.

20 After the outsole stitching operation has been completed the intermediate section B may be replaced in the shoe and the manufacture of the shoe continued in the usual manner. It is obvious that, if desired, the 25 shoe might be made on an ordinary last and this last replaced by the last shown in Fig. 3, just before the outsole stitching operation is begun. After the completion of the outsole stitching operation the intermediate section B could be placed in the 30 last in the shoe and the manufacture of the shoe continued on this last, or the last shown in Fig. 3 could be withdrawn and replaced again by the last on which the making operations have been performed up to the out- 35 sole stitching operation.

What is claimed as new is:

1. A last, having a toe portion, a heel portion, a plate connecting said toe and 40 heel portions and forming the bottom of the last, said plate being operative to hold said portions in coöperating relationship with each other, and an intermediate last portion constructed to fit between said toe and heel portions to complete the last, said 45 intermediate portion including the entire shank portion of the last above said plate and being constructed and arranged to be removed while the last is in the shoe, leaving said toe and heel portions in their 50 normal positions in the shoe.
2. A last, comprising a forepart having toe and instep supporting surfaces, a heel portion, and a plate connecting said toe 55 and heel portions and forming the bottom of the last, said toe and heel portions being separated by a space lying opposite the shank portion of the shoe for which the last is intended.
- 30 3. A last, comprising a forepart having

toe and instep supporting surfaces, a heel portion, and a plate connecting said toe and heel portions and forming the bottom of the last, said toe and heel portions being separated by a space lying opposite the shank 65 portion of the shoe for which the last is intended, and said plate being in two sections hinged together at a point between said toe and heel portions.

4. A last, comprising a forepart, a heel 70 part, and means connecting said parts for relative swinging movement to collapse or extend the last and constructed and arranged to hold them in coöperative relationship to each other but to leave the upper 75 of the shoe in which the last is positioned without lateral support in the region of the shank.

5. A last, having a toe portion, a heel 80 portion, a plate connecting said toe and heel portions and having a surface forming a portion of the tread face of the last, and a removable intermediate part including the shank portion of the last constructed and arranged to be removably supported 85 between said toe and heel portions, the sides of said toe and heel portions adjacent to the tread face of the last and the edge surfaces of said plate extending approximately 90 at right angles to the tread face of the last.

6. A last comprising a forepart, a heel 95 part, means connecting said parts for relative swinging movement to collapse or extend the last and constructed and arranged to hold said fore and heel parts in coöperative relationship to each other but to leave the upper of the shoe in which the last is positioned without lateral support in the region of the shank, and an intermediate 100 last portion constructed to fit between said fore and heel parts to complete the last and arranged to be inserted in its operative position or removed therefrom while the last is in the shoe.

7. A last having a forepart, a heel part 105 spaced from the forepart, a plate connecting said parts and forming the bottom of the last, and an intermediate portion constructed to fit between said toe and heel portions and containing the upper supporting 110 surfaces of the last that overhang the edges of said plate in the region of the shank of the shoe, said intermediate portion being constructed and arranged to be inserted in its operative position or removed 115 therefrom while the last is in a shoe without disturbing said fore and heel parts.

In testimony whereof I have signed my name to this specification.

JOHN R. McLAUGHLIN.
